ELECTRIC SYSTEM FOR CONTROLLING MOTIONS

Max Lattmann, Zurich, Switzerland

Application July 18, 1946, Serial No. 684,615
In Switzerland July 14, 1945

Section 1, Public Law 690, August 8, 1946

1 Claim. (Cl. 318—19)

1

The present invention relates to systems for controlling motions and in particular for registering and reproducing motions with the aid of an equipment for magnetic recording of electrical signals.

The method of generating a motion, in particular a rotary motion with a determined time lag relative to an original motion, with the aid of a magnetic recording and reproducing equipment is already known. It consists in transmitting direct current impulses to the movable steel ribbon. The greater the velocity of the original motion, the closer these impulses follow one another. At high velocity it may happen that single impulses are lost in the magnetic recording and reproducing equipment, with the result that the retarded motion no longer corresponds to the original motion. The present invention aims at creating an arrangement in which such errors in the retarded reproduction of an original motion cannot possibly occur.

In a specific preferred embodiment the invention comprises an electric follow-up control system in which the velocity of an output member depends on the lag between the controlling motion and the follow-up motion, and in which the latter is generated by a synchronous motor to which is fed a three-phase current of variable frequency. This three-phase current is generated with the aid of a modulating device in which a three-phase current of constant frequency is modulated with a monophase current whose frequency is proportional to the lag between the controlling motion and the follow-up motion. Electric follow-up control systems of this kind are already known. For the purpose of generating a second follow-up motion whose temporal course tallies exactly with that of the first follow-up motion but is retarded relatively to the latter by a time which may be chosen at will, this embodiment of the invention comprises a second synchronous motor and a device for recording and reproducing alternating currents by means of a magnetizable carrier. Like the first this second synchronous motor is fed by a three-phase current of variable frequency generated in a modulating device by the modulation of a three-phase current of constant frequency with a monophase current of variable frequency. This monophase current is generated by the above-mentioned recording and reproducing equipment. Here a monophase current is recorded on a magnetizable carrier by means of a recording head to which is fed the monophase current utilized in the follow-up control system. This recording

2

induces in a reproducing head, placed at a certain point (which may be chosen at will) of the carrier the monophase current intended for feeding the modulating device of the second synchronous motor.

The nature of the invention will be more fully understood from the following detailed description and by reference to the accompanying drawing of which

10 Fig. 1 is a general diagram of an arrangement according to the invention;

Fig. 2 shows in detail the circuit 17 in Fig. 1;

Fig. 3 shows modulating devices 18 and 26 in Fig. 1;

15 Fig. 4 shows a part of the arrangement in Fig. 1 in an altered form.

The original motion is described by shaft 10 of differential condenser A. This comprises plate 11 attached to shaft 10 and the pair of plates

20 12, 13 attached to shaft 14, which plates abut on each other forming a gap. Plate 11 and the pair of plates 12, 13 form part of two concentric, cylindric surfaces. Differential condenser A is fed by transformer 15 connected with a source

25 of alternating current, and whose secondary winding is connected with the pair of plates 12, 13. When plate 11 is in a position symmetrical with both plates 12, 13, there is no voltage between plate 11 and the middle of the secondary

30 winding of transformer 15. On the other hand a voltage is generated as soon as plate 11 is moved from this position in either direction, which can be brought about by the rotation of shaft 10 or of shaft 14.

35 The voltage thus produced is fed via leads 16 to a circuit 17 that acts as a source of alternating current whose frequency can be increased or decreased relatively to a mean frequency f by means of the voltage generated in differential

40 condenser A. This frequency is increased or decreased according to the sense of the relative displacement of the plates of condenser A and the magnitude of the variation Δf depends on the magnitude of this displacement. The alternating voltage produced in circuit 17 is fed on the one side to modulating device 18 of a first follow-up equipment B and to recording head 19 of a magnetic recording and reproducing equipment C on the other. The endless steel ribbon 20 of

45 the latter is advanced with uniform speed by means of drums 21, 22 and driving members not shown in the drawing. On this ribbon is continually recorded the alternating current fed to recording head 19. After a certain time the recording induces in the winding of reproducing

head 23 an alternating current of exactly the same frequency as that generated by circuit 17. This alternating voltage is fed to the modulating device 26 of a second follow-up equipment D. By erasing head 24 connected to the battery 25 all recordings on steel ribbon 20 are cancelled before the relative points of the ribbon again reach recording head 19.

In each of the two identical follow-up equipments B, D besides the modulating device 18, 26 there is a three-phase synchronous motor 27, 28. The rotor of motor 27 is connected with shaft 14 of differential condenser A, whereas rotor 28 via shaft 29 drives the member to which should be transmitted the retarded follow-up motion. Each of the modulating devices 18, 26 is fed via common three-phase line 31 by a source of alternating current whose frequency is the same as the mean frequency f produced by circuit 17. Furthermore, each of the modulating devices is connected via a three-phase line 32, 33 with the windings of the rotor of the appurtenant motor 27, 28.

Fig. 2 shows one embodiment of the circuit 17 of Fig. 1. It will be seen that there are two repeating coils 36, 37 whose secondary windings are each connected to a pair of terminals of a ring modulator 38. The primary winding of repeating coil 36 is connected with leads 16 of Fig. 1, whereas the primary winding of repeating coil 37 is connected with a source of alternating current of the same frequency as that fed to the primary winding of transformer 15 of Fig. 1. The middle of the secondary windings of both repeating coils 36, 37 is connected with the input terminals of a filter circuit 39 composed of two shunt condensers 40 and a series coil 41 and intended to suppress harmonics generated in the modulator 38. Resistance 42 is connected to the output terminals of filter circuit 39 and forms part of the grid circuit of amplifier tube 43 whose anode circuit comprises one winding 44 of a repeating coil 45 and resistance 46. The direct current coming from amplifier tube 43 serves to pre-magnetize repeating coil 45. Winding 46 and condenser 47 form an oscillatory circuit connected with the grid of tube 48. In addition to repeating coil 49 shunted by the plate resistance 51 the anode circuit of this tube comprises reactance winding 50 of repeating coil 45 and a series resistance 52. The plates of both tubes 43, 48 receive a positive voltage from lead 53 connected to the positive pole of a battery not shown in Fig. 2.

When there is no voltage in the primary winding of repeating coil 36, and this is the case when there is no displacement in condenser A, no current flows through resistance 42 owing to the symmetry of the circuit. This situation is altered as soon as a displacement occurs in condenser A, since as a result of the voltage applied to transformer 15 (see Fig. 1) in the secondary winding of repeating coil 36 a current is generated which is in phase or in phase opposition to the current generated by the voltage applied to the primary winding of repeating coil 37 according to whether the displacement in condenser A took place in one direction or the other. As a result of these currents modulation products make their appearance in modulator circuit 38. The only one of these to reach resistance 42 is that which corresponds to the difference between the two alternating voltages acting on modulator circuit 38 and as in the case in point the frequencies are the same, which

forms a direct current. Its direction depends on whether the phases of the two voltages applied to the primary windings of repeating coils 36 and 37 are the same or opposed. In order to fix the steady plate current a constant direct auxiliary voltage not shown in Fig. 3 is applied to the grid of the tube 43. When there is a displacement in condenser A, to this auxiliary voltage is added the voltage drop in resistance 42, so that a displacement in one direction or the other results in an increase or decrease of the plate current relative to the steady plate current. When there is no displacement in condenser A the steady plate current flowing through tube 43 determines the premagnetization of repeating coil 45 and thus defines the mean value f of the frequency produced by tube 48. Any variation of the direct current that flows through winding 44 causes an increase or decrease Δf of this frequency f dependent on the magnitude of the displacement in condenser A.

Fig. 3 shows modulating devices 18 and 26 of Fig. 1. Here the alternating current of frequency $(f \pm \Delta f)$ arriving by leads 55 from repeating coil 49 of Fig. 3 is fed in parallel to the primary windings of three repeating coils 56, 57 and 58. Each of these repeating coils forms together with a further repeating coil 59, 60, 61 and a rectifier circuit 62, 63, 64 a modulating device composed in the same manner as shown in Fig. 3. To each of the repeating coils 59, 60, 61 is connected one phase of a three-phase current of frequency f . The primary windings of these repeating coils are connected in star connection to three-phase line 65, whereas their secondary windings as well as those of the repeating coils 56, 57, 58 are each connected with two terminals of one of the rectifier circuits 62, 63, 64. A derivation is made from the middle points of the secondary windings of both repeating coils of each modulating device and conducted to a filter circuit composed of an induction coil placed in series and two shunt condensers. These filter circuits do not permit of the passage of any frequency greater than the difference between the modulating frequency $f \pm \Delta f$ and the mean frequency f . The low-frequency alternating currents present at the output terminals of the three filter circuits 66, 67, 68 are led preferably over amplifiers not shown in Fig. 3 and via three phase line 32 or 33 of Fig. 1 to one of the windings of three-phase synchronous motor 27 or 28 of Fig. 1. These motors can advantageously take the form of synchronous reaction type motors which operate without direct current excitation and whose rotating parts can therefore be constructed with a very small moment of inertia.

The arrangement described above operates as follows:

If when shaft 19 is at rest shaft 14 occupies a position in which plate 12 is symmetrical with plates 12, 13, there is at the output terminals of circuit 17 an alternating voltage whose frequency is equal to the frequency of the source of alternating current that feeds line 31. This alternating voltage is led direct to modulating device 18 and via recording and reproducing equipment C to modulating device 26. In both of these modulating devices it modulates each phase of the three-phase current arriving via line 31. Filter circuits 66, 67, 68 of Fig. 4 allow the passage to motors 27 and 28 only of those products of modulation that correspond to the difference between the frequencies of the output voltage of circuit 17 and of the three-phase current led to

line 31. As these frequencies are equal, the rotor windings of both motors receive a direct current. Therefore both motors remain at rest.

When shaft 10 is displaced from this position of symmetry, at the output terminals of circuit 17 a voltage appears whose frequency is increased or decreased relatively to the mean frequency f by Δf . As a result of this at the output terminals of modulating device 18 a three-phase current of frequency (Δf) is generated, which sets in motion motor 27 with a speed corresponding to this frequency. The direction of rotation is chosen such that shaft 14 is rotated in the same sense as shaft 10, viz., shaft 14 follows shaft 10. In modulating device 26 the variation of frequency of the output voltage of circuit 17 only makes itself felt with a delay determined by the speed of steel ribbon 20 and the distance between recording head 19 and reproducing head 23. After this delay motor 28 also starts revolving and its motion is exactly equal to that of motor 27 but with the above mentioned time lag. If it is desired to vary the time lag between the motions of motors 27 and 28, this is best achieved by varying the distance between recording and reproducing heads 19 and 23. If, for instance, reproducing head 23 is displaced, this causes a variation of this voltage induced in it, since during this displacement the speed of steel ribbon 20 relative to recording head 19 differs from that relative to reproducing head 23. As a result of this the motion of motor 28 would no longer be a true reproduction of the motion of motor 27. In the following it will be explained how the error arising from the displacement of one or the other of heads 19, 23 may be eliminated.

Fig. 4 only shows the rotor of the synchronous motor 28 and the reproducing head 23 of the arrangement illustrated in Fig. 1. For the purpose of displacing reproducing head 23 along the recording ribbon screw spindle 79 is provided which terminates in hand crank 71 and engages in an aperture 72 in reproducing head 23. Screw spindle 79 is also connected mechanically via the two conical gears 73, 74 and shaft 75 with differential gear 76, from which latter a second shaft 77 is fixed to the rotor of synchronous motor 28, while a third shaft 78 is fixed to the member to be driven. From Fig. 2 it is obvious that when reproducing head 23 undergoes no displacement shaft 75 also remains at rest, so that the motion of motor 28 is transmitted, as in the arrangement illustrated in Fig. 1, direct to shaft 78. When screw spindle 79 is actioned by hand crank 71 reproducing head 23 is displaced in one direction or the other and shaft 78 receives an additional drive. By suitably choosing the ratio of differential gear 76 and the pitch of screw 79 the increase or decrease of the angular velocity of shaft 78 caused by the action of differential gear 76 via shaft 75 is made equal in magnitude and opposite in sign to the increase or decrease caused by the displacement of reproducing head 23. Should it be desired to displace the recording head instead of the reproducing head, the error

thus caused in the follow-up of synchronous motor 28 can be eliminated by transmitting an additional motion to synchronous motor 27 in a manner similar to that just described.

5 In the example described above purely mechanical means were provided for compensating the error caused by the displacement of the reproducing head. The following is an explanation of how the arrangement in Fig. 1 can be 10 altered in order to introduce electrical compensation of the error. For this purpose the magnetic recording and reproducing equipment is provided with three additional sets of recording and reproducing heads. The three additional 15 reproducing heads, are mechanically connected with reproducing head 23 in such a way that all four always undergo the same displacement. Furthermore, modulating device 26 is no longer fed direct by three-phase line 31, but is connected 20 with the windings of the three additional reproducing heads while line 31 feeds the windings of the additional recording heads. In consequence of this, when the time lag is varied, not only the frequency of the voltage induced in the winding 25 of reproducing head 23 is altered, but also the frequency of the three-phase alternating voltage that feeds modulating device 26, so that the above-mentioned error in the follow-up of motor 28 is likewise eliminated.

30 What is claimed is:

In a system for controlling follow-up movements in combination a device comprising two parts displaceable with respect to each other of which a first part is primarily moved while the 35 second part moves in accordance with a first follow-up movement; a first driving means comprising a polyphase synchronous motor driving said second part and an electric modulating device, in which each phase of a polyphase current 40 of constant frequency is modulated by a monophase current of variable frequency, the polyphase current generated in the modulating device being fed to said synchronous motor; an electric oscillatory circuit generating a monophase current whose frequency depends on the relative displacement of the two said parts; a second driving means, comprising a polyphase synchronous motor generating a second follow-up movement and an electric modulating device in 45 which each phase of a polyphase current of constant frequency is modulated by a monophase current of variable frequency; a magnetic recording and reproducing system, comprising a carrier moved with constant speed, a recording head to which is fed said monophase current of variable frequency feeding also the modulating device of said first driving means and a reproducing head, which is connected to the modulating device of said second driving means, the temporal course of said two follow-up movements being the same, the second movement being however delayed by a fixed time with respect to the first movement.

MAX LATTMANN.
